UNITED STATES PATENT OFFICE.

WRIGHT BOLTON, JR., OF NEW BEDFORD, MASSACHUSETTS.

EDGE-WINDING COMPRESSOR FOR WINDERS.

Application filed March 17, 1924. Serial No. 699,683.

This invention relates to winding machines, for example textile winding machines having a driven spool or warp-beam upon which the winding mass is in operative contact with a driving frictional surface, such as the usual tractor drum or roll or belt, or other device depended upon for simultaneous rotation and compression of the winding.

10 In machines of the kind referred to, practical considerations of variations from the intended spacing and from accurate perpendicularity to the axis of the spool or warp-beam heads dictate the use of a driving or tractor drum or like frictional driving surface sufficiently narrower than the smallest expected free space between the head flanges to permit the heads to straddle the driving surface without possibility of binding. The 15 winding space on the warp-beam, spool or jack spool may exceed the driving surface in width by an inch or more in practice.

This neither prevents nor limits the winding upon the spool or beam, hereinafter referred to as the winding container, but does 20 result in producing a wound mass which, though laid on throughout the greater part of the winding space under uniform conditions of compression, has end sections or 25 edges laid on without the benefit of constant compressive contact with the driving surface. Consequently these edge regions tend to irregularity, usually increasing in diameter faster than the normal parts of the winding, and therefore containing longer windings than normal parts of the wound container wound by the same number of revolutions of the winding container. This defect, which is serious in any wound package, 30 is particularly objectionable in the case of 35 warps or warp sections wound for slashing or for direct use in a loom, since it results in a warp having selvage regions, or the edges of sections, slacker and longer than the middle regions. Corrective treatment in the 40 slasher or loom is practically impossible without serious waste of yarn; and wavy or curved places or slack selvages result in the 45 cloth.

50 Objects of this invention are to obviate such defects of wound packages by providing to maintain substantially uniform compression of the wound mass throughout the space between the heads or flanges of the 55 wound container during winding; to provide

edge-winding compression devices auxiliary to the wound mass driving and compression means adaptable to existing winding machines without change; to provide auxiliary devices of the kind indicated capable of co-operating with spools or warp-beams having heads not accurately perpendicular to their axes, and adapted to maintain even compression when the wound mass is not accurately cylindrical, or when there is axial reciprocation or creeping of the winding mass; and to provide for removing the finished packages and beginning new windings without interference by the auxiliary device with rapid removals and replacements of the container.

The invention will be explained in connection with preferred forms only of the devices chosen for illustration in the accompanying drawings, in which:

Fig. 1 is a front elevation of a detail of a familiar type of warper showing a warp-beam, the tractor drum, the side frames, and the edge compressor devices in position for operation;

Fig. 2 is a detail right side elevation of the parts shown in Fig. 1;

Fig. 3 is a detail partly in vertical section of one of the auxiliary compressor rolls;

Fig. 4 is a detail partly in section on line 4-4 of Fig. 1 showing the operation of the rotary compression weight;

Fig. 5 is an elevation, showing the roll restrained, of a modified auxiliary compressor roll; and

Fig. 6 is a longitudinal section of the device of Fig. 5, showing the roll released for operation.

Referring now to Figs. 1 and 2, the winding machine may comprise any or all of the usual agencies, such as guiding combs, lease forming devices, supports for the drop-wires of breakage-actuated stop-motion devices, including a power-release device; a warping reed, and a delivery guide roll, all supported by the end frames 1, all familiar in the art, and not herein shown. Also as usual in the art, the machine includes a tractor-roll or belt, shown as the drum 2 on the horizontal shaft 3, which may be driven in any usual way, for example by a belt, not shown, at a constant peripheral speed. Pivoted on shaft 4, the machine includes supports such as the radius-arms 5 for the winding container having bearing notches 6 or other

appropriate bearings for the spindle 7 of the spool or warp-beam 10 having heads 12 straddling the ends of drum 2, against which the surface of the winding layer rests with a compressive force determined by the weight of the container 10, and, if desired, by auxiliary weights 13 adapted to be hung on the supporting arms 5.

The winding yarn *w* thus runs from the guide roll, not shown, on to the wound layer of the container 10 at the opposite side of a layer from the point of compression and exertion of the necessary frictional driving torque by drum 2. The length of the container 10 between its heads 12 necessarily exceeds the length of drum 2, and this results in wound regions *x*, *x*, which, without assistance, are inevitably soft, spongy, enlarged and contain more yarn than the normal middle portions of the winding which have been laid under the constant compression of drum 2. The regions *x* may be of different and irregular widths, due to irregularity of the heads 12 or slow reciprocal axial motion of the container 10.

This invention provides for the compression of the regions *x* to a predetermined degree substantially conforming to the remainder of the winding, by means acting upon the edges of the winding to compress them variably according to excess of diameter of the edge windings. Preferred instruments for this purpose, as shown, are arranged to compress edge regions exceeding in diameter the central regions at a point, as measured along the winding layer, more remote from the place of contact of the yarns *w* with the previous winding than is the place of contact of the last layer of yarn with the drum 2, in order not to apply compression to a layer insufficiently wrapped about the winding surface by the tension of the yarn. The instruments preferred and shown are also caused so to act upon the wound surface of the container as substantially to have no effect upon the pressure of the winding upon its driving and compressor surface, such as the drum 2, and are provided to be readily removable from contact with the container, and may be arranged to bear upon the winding with reduced pressure whenever the machine stops automatically or at will of the operator.

These instruments comprise freely rotatable and axially movable rolls 15, 15, and mounting and positioning mechanism for these rolls adapted severally to maintain them in contact with the winding mass and the container 10 under a predetermined relatively constant pressure acting on the upper side of the winding periphery, the direction of the pressure being toward the center of the container 10.

In order to provide for the equipment of existing machines, and for other purposes,

it is preferred that the devices for holding and moving the rolls 15 shall be such as to be readily attached to the frames of existing machines, but it will be understood that any construction providing for the effective position and effective pressure on these rolls may be employed. As shown in Figs. 1 and 2, the preferred devices comprise attachable bearing plates or blocks 16 alike but symmetrically formed for each side of the machine, as best shown in Fig. 1, and having holes for attachment screws or bolts 17 for ready adjustment to conformity with containers of different sizes, or different arrangements of the drum corresponding to the drum 2 of the drawings. Plate 16 provides a bore 18 and an integral or attached sector 19 having a slot 20 concentric with the bore 18 in which hole and slot respectively is held a stud shaft 21 and the hold-down bolt 22 projecting from a bracket arm 23, in turn providing a bearing for a shaft 25 about which the roll 15 can move as a center. It will be observed that the position of the shaft 25 may be adjusted along the sector slot 20 suitably to control the locus of motion of the rolls 15. A preferred form of mounting permitting this motion of the rolls 15 and permitting control of the pressure upon the rolls 15 as presently explained, comprises a radial arm 26 integral with or attached to the hub of a sector gear 27 in turn having a bearing on the shaft 25. The structures 26, 27 may be held against end-wise movement on the shaft 25 by a head 28 integral with or attached to the inner end of the shaft 25.

The attachment block or plate 16 is provided with an inwardly projecting lug 30 providing a bearing for a short shaft 31 projecting outwardly through a hole in the frame 1 and having fixed on its inward end a gear sector 32 meshing with the gear 27.

The outer end of the shaft 31 carries one member 33 of a pin or other unipositive clutch, of which the other member 34 may be integral with or attached to the hub of a counterweight sector 35 confined against freedom of longitudinal motion on the shaft 31 by a collar 36.

The radius arm 26 at a suitable distance from the center 25 to clear the head flange 12 of a container of any expected diameter is provided with a rigid attachment, as shown, in the form of a pair of shoulder-bolts 38, for an inwardly extending arm 39 in turn carrying an angle bracket casting 40 upon the inner end of which there may be suitably mounted a holding or bearing block 41 for a horizontal shaft 42, Fig. 3, upon or with which the roll 15 turns.

It will be understood without further explanation that the above mentioned structures are provided at each side of the machine preferably in like form, but sym-

metrically right and left handed for the right hand and left hand frames 1 respectively.

Referring now to Fig. 3, the roll 15 may be formed as a sleeve having its free end closed by a screw plug 50 having a polished face 51, and having an internal bearing sleeve 52 to take over the shaft 42 upon which it is held by the washer 53 and screw 54 against the thrust of a light compression spring 55 housed in the space within the sleeve 15, between the end of the bearing sleeve 52 and the end of the block 41. This arrangement is such as to provide axial freedom of movement for the sleeves 15 and 52 through the range permitted by the compressed state of the spring 55 and the washer 53.

When a new spool or beam is to be mounted or a full spool or beam is to be doffed, it is desirable to be able to remove the rolls 15 from their operative position; this is preferably accomplished by locking the said rolls in their inner position for which purpose a pin 57 may be provided in the block 41, to take into any one of several bayonet-clutch slots 58, 59. Preferably these clutch slots are provided by an inclined slot part 59 penetrating the full thickness of the sleeve 15 and joining a broached-out slot 58 not penetrating to the surface of the roll 15.

As best shown in Figs. 5 and 6 the auxiliary compressor roll shaft 61 may be arranged to have endwise freedom of movement, for the purpose of providing for endwise motion of the rolls 15. In this case the block 41 provides a sliding bearing bore 60 for the reduced end of the roll shaft 61, which may have a stop collar 62 and an enlargement 63 co-operating with the compression spring 64 housed in an enlarged bore 65 in block 41. The outboard end of the enlargement 63 may be received within a recess 64 in the end of the roll 15 which is provided with an internal bearing sleeve 66, and is without substantial freedom of motion in respect to the shaft 61, upon which it is held by the washer 67 and screw 68.

The counterweight sector 35 is normally displaced against gravity by its connection to the shaft 31, and according to its position transmits through said shaft a variable pressure countervailing in part the variable pressure exerted upon the rolls 15 by the weight of the roll supports. It will be observed that the opposite motion toward the upper dead center or central position of eccentric weight of the roll support 26, 39 is accompanied by approach of the counterweight 35 to its dependent position of rest, so that the effective pressure on the roll 15 is substantially constant.

It is desirable to remove this pressure when the winding stops. This may be provided for by a hole 36 in the sector 35 and a cord 37 connected through pulleys or bell-

hanger's connections, not shown, to the movable element of the power release devices of the machine. Such a connection may be performed by any mechanic in accordance with the different particular arrangements of the machine with which the devices of this invention are employed. A pull on connection 37 lifts rolls 15 away from the wound mass.

In operation the rolls 15 rest upon the winding and compressed layers of the normal part of the winding throughout the greater part of their contact with the wound mass upon the normal parts of which their additional pressure is without effect. The edge windings desired to be controlled occupy, as shown at α , only a small fraction of the width of the compression rollers 15. If there is substantial slack in winding, the regions α will grow to a slightly larger diameter than the adjacent parts of the winding and when this happens the whole structure 15, 40, 29, 26, 27 etc., is rotated about the center 25 by the weight of these parts except so much of this weight as is counterbalanced by the thrust of the sector 35 communicated by the gear 32. When the whole thrust on the auxiliary rolls 15 is carried by the narrow regions α , the local compression is considerable. This condition continues until the rolling action on the softening edge winding has produced a sufficient compression again to bring the adjacent edge winding into conformity with the diameter of the remainder of the winding.

If the heads of the winding container are not accurately perpendicular, or if the winding container reciprocates slowly or rapidly in the direction of its axis, the longitudinally and oppositely spring-pressed rolls 15 are able to follow this motion, so that the polished ends 51 of the rolls run in close contact with the inner surface of the heads 12 of the winding container. It has been found in practice that there is no considerable resistance to the turning of the warp-beam or spool by contact with the polished heads of these rolls. This again is due to the axial freedom of motion of the rolls; they yield to pass obstructions which otherwise would lock the heads 12 against motion.

When a full spool or beam is to be removed, the auxiliary rolls and their mountings are turned back out of the way by pulling on the connections 37; when the eccentric center of gravity of the roller supports 26, 39, etc., has passed the vertical from shafts 25, the auxiliary rolls will remain in the idle position, the clutches 33, 34, permitting the weights 35 to swing to their idle dependent position, the operative position of all the parts being restored when the rolls 15 and their supports are again swung forward into contact with a new winding.

I claim:

1. A winding machine having therein means for driving a winding container, means for maintaining the winding mass in contact with the driving means adapted to 50 compress the winding layers throughout the region of driving contact, in combination with an auxiliary compressor roll having axial freedom of motion, and means for maintaining said auxiliary roll in contact with portions of the winding including portions not compressed by contact with said driving means.
2. A winding machine having therein means for driving a rotary winding container, means for maintaining the winding mass in contact with the driving means adapted to compress the winding layers throughout the region of driving contact, in combination with an auxiliary compressor roll, means permitting rotation of said roll on an axis parallel to the axis of rotation of the winding container and means for stressing said auxiliary roll into contact with portions of the winding, including portions not compressed by contact with said driving means, in a direction at right angles to said axes of rotation.
3. In a winding machine having therein means for rotating a winding container on its axis, an auxiliary edge-winding rotary compressor roll, in combination with gravity-actuated means adapted to stress said roll against the winding mass in a direction perpendicular severally to the axes of rotation of said container and said auxiliary roll.
4. In a winding machine having therein means for rotating a winding container on its axis, an auxiliary edge-winding rotary compressor roll, in combination with gravity-actuated means adapted to stress said roll against the winding mass in a direction perpendicular severally to the axes of rotation of said container and said auxiliary roll, and means permitting axial motion of said auxiliary roll.
5. In a winding machine having therein means for rotating a winding container on its axis, an auxiliary edge-winding rotary compressor roll, in combination with gravity-actuated means adapted to stress said roll against the winding mass in a direction perpendicular severally to the axes of rotation of said container and said auxiliary roll and means for relieving said auxiliary roll of a portion of said stress.
6. In a power-actuated winding machine having therein means for rotating a winding container on its axis, an auxiliary edge-winding rotary compressor roll, in combination with gravity actuated means adapted to stress said roll against the winding mass in a direction perpendicular severally to the axes of rotation of said container and said auxiliary roll and means for relieving said auxiliary roll of a portion of said stress
- adapted to be actuated by a connection to the power-control devices of the machine to remove the said auxiliary roll from contact with the material being wound.
7. In a winding machine, means for supporting a winding container for compressive contact with the surface of a driving and compressing roll by motion in a direction toward said roll, in combination with an auxiliary edge-winding compressor roll, and means for supporting said auxiliary roll for freedom of motion against the surface of the winding in a direction crosswise of the direction of freedom of motion of the winding container.
8. In an edge-winding compressor device for use with winding machines, the combination with a headed winding container and means for rotating said container of an auxiliary roll and a support therefor having an offset adapted to straddle the head of the container, means permitting axial freedom of motion of the auxiliary roll toward and away from one of said heads, and means permitting said auxiliary roll and support to move toward and away from the axis of rotation of said container.
9. In an edge-winding compressor, an auxiliary roll and a bearing therefor permitting axial freedom of motion, a spring urging the roll in one axial direction, and means for locking the roll against motion in said direction.
10. In an edge-winding compressor device for use with winding machines, the combination with a headed winding container and means for rotating said container of an auxiliary roll and a support therefor having an offset adapted to straddle the head of the container, a shaft for said support, means for controlling the compressive stress on said roller by turning stresses applied to said shaft, and bearing means for said shaft adapted to be adjusted in relation to the locus of motion of the axis of the winding container.
11. In an edge-winding compressor device, an auxiliary roll, a mounting therefor carried by a shaft, gravity means for turning said shaft to apply the compressor roll to the winding, and a clutch adapted to release said gravity means from its connections to said shaft in one position of the parts.
12. In an edge-winding compressor device, an auxiliary roll, a mounting therefor carried by a shaft, and adapted to hold said roll in operative position by gravity, gravity means tending to turn said shaft to counterbalance a part of the pressure of the compressor roll on the winding, and a clutch adapted to release said gravity means from its connection to said shaft.
13. In combination with a beam head, an arm, a roller, means to support the arm and roller with an end of the latter in contact

with the beam head, and the warp upon the beam, and means to tension the roller axially thereof.

14. In combination with a beam head, relatively short spring pressed means held in contact with said head, and exerting tension in an axial direction on the head and means to tension the first named means to

cause same to exert tension on the warp which is being wound upon the beam, to prevent bunching of the same adjacent to the said head, as described. 10

Signed by me at New Bedford, Mass., this 14th day of January, 1924.

WRIGHT BOLTON, JR.
